HOOK FOR GARMENT HANGERS

Carl N. Bergstrom, Portland, Oreg.

Application November 20, 1944, Serial No. 564,369

4 Claims. (Cl. 223—88)

This invention relates generally to garment hangers, and particularly to that class of collapsible coat hanger described in my Patent 2,296,624.

The main object of this invention is to provide a hook for collapsible paper hangers which will be simple to construct, easy to apply, secure in its holding action, devoid of corners which would catch fragile garments, and having a swivel hook enabling the hanger to assume any angular position with relation to the plane of the hook.

I accomplish this and other objects in the manner set forth in the following specification as illustrated in the accompanying drawing, in which:

Fig. 1 is a front elevation of a coat hanger showing the first step in the application of a hook thereto.

Fig. 2 is a view similar to Fig. 1, showing the second step in the application of the device.

Fig. 3 is a fragmentary view showing the third step in the application of the device.

Fig. 4 is a fragmentary view showing the fourth step in the application of the device.

Fig. 5 is a perspective view of the hook clamp.

Fig. 6 is a section taken along the line 6—6 in Fig. 3.

Fig. 7 is an enlarged end elevation of the hook clamp, showing the manner of confining the hook within the clamp members.

Similar numerals refer to similar parts throughout the several views.

Referring in detail to the drawing, there is shown a paper garment hanger consisting of a channel shaped member 14 with inclined shoulder supporting members 15 and 16, whose lower ends 17 are preferably integral with the member 14. The members 15 and 16 are also channel shaped and overlap each other at their upper ends and have a common pin slot 18 formed therethrough.

Hook clamp

The hook clamp consists of a vertical bar 19, having an open eye 20 formed at its lower end and a closed eye 21 formed at its upper end, while a pin 22 projects from the middle portion of the bar 19 and is curved somewhat, as is shown in Fig. 7. The eyes 20 and 21 are in alignment to receive the hook shank 24, while the pin 22 exerts a pressure against the side of the hook shank 24. The hook clamp may assume a variety of forms, but must have a closed eye at one end and open eye at the other end, and a locking pin at an intermediate portion. Although not necessarily so,

it is desirable to have the open eye member 20 on the lower side of the device.

Hook member

5 The hook shank 24 has a curved end 25, which is made large enough to accommodate the carrying apparatus in large cleaning establishments, while the hook shank 24 is straight and terminates in a head 26 at its lower end. The junction 27 of the hook shank 24 and the hook end 25 is somewhat rounded and has a definite part to play in the assembling of this hook and the hanger which it supports. The steps taken in the assembling of this device are best illustrated in Figs. 1 to 4 of the drawing.

10 It will be seen, for example, that in Fig. 1 the hook clamp is supported by means of its closed eye 21 from the head 26 of the hook shank 24. In Fig. 2 it will be observed that the pin 22 has been passed through the slot 18, while the closed end 21 is above and the open end 20 is below the hanger members. It will be noted that in this figure the hook shank 24 has been moved down to a point where it can engage the open hook 20.

15 In Fig. 3 is shown a condition in which the hook shank 24 has been drawn up through the eyes 20 and 21, thereby compressing the uppermost hanger ends but having the pin 22 at the bottom of the slot 18. The final movement brings 20 the parts to the position shown in Fig. 4, in which the pin 22 reaches the upper part of the slot 18 and the point 28 of the open eye 20 is embedded in the material of the hanger portions 15 and 16. It will be noted that now the members 15 and 30 16 are rigidly bound together and that the only portion of the device which might catch fabrics, 35 namely, the end 28, is embedded in the paper of the hanger itself.

25 In illustrating this invention, little attempt has 40 been made to hold the parts to the precise scale, as this will vary considerably with the requirements and does not affect the principle or operation of the present invention.

I claim:

- 45 1. A support for coat hangers consisting of a hook clamp having an elongated bar provided with a closed eye at one end and an open eye at the other end thereof in combination with a hook having an elongated headed shank adapted 50 to occupy both of said eyes simultaneously in a manner to clamp a portion of said hanger between said shank and elongated bar when said headed end is brought into engagement with said open eye.
- 55 2. A support as defined in claim 1 characterized

by having a pin projecting from said elongated bar between said eyes and extending across the space between said hook shank and bar.

3. A support for garment hangers consisting of a straight shank having a head at one end and a hook at the other end, the junction of said hook and shank constituting a bend, and a hook clamp consisting of an elongated bar having a closed eye formed laterally at one end and an open eye formed laterally at the other end, and having a pin projecting from said bar between said eyes and in the same direction, the spacing of said eyes and the length of said shank between

the head and bend providing a means for threading said shank through both eyes before said head is brought into engagement with said open eye.

4. A support for garment hangers consisting of a hanger element provided with a horizontal perforation in its uppermost end, a headed hook shank engaging one of said hanger portions, a hook clamp bar engaging the other side of said hanger portion, said bar having a point extending into said perforation and having eyes above and below said hanger portion through which said hook shank extends.

CARL N. BERGSTROM.
